UNITED STATES PATENT OFFICE

EDWARD L. C. CLARK, OF DEDHAM, AND SKIDMORE O'HARA, OF WALTHAM, MASSACHUSETTS, ASSIGNORS TO O'HARA WALTHAM COMPANY, OF WALTHAM, MASSACHUSETTS, A CORPORATION OF MASSACHUSETTS

METAL TILE

Application filed April 3, 1929. Serial No. 352,128.

This invention relates to a new and useful improvement in metal tiles more especially intended for use in the construction of walls and ceilings but adapted for other uses, and which are made of sheet metal plates shaped to imitate in appearance solid tiles.

One object of the invention is to provide metallic tiles of the character described of simple construction, and which may be easily and accurately laid in proper alinement and interengaging arrangement and so constructed that they are reversible end for end.

The invention will be more fully understood from the following description when taken in connection with the accompanying drawings and the novel features thereof will be pointed out and clearly defined in the claims at the close of this specification.

In said drawings:

20 Fig. 1 is a side elevation of a plurality of tiles embodying the invention laid up in courses in vertical arrangement to form the interior finish for the side wall of a room.

Fig. 2 is a section on line 2—2 of Fig. 1.

25 Fig. 3 is a section on line 3—3 of Fig. 1.

Fig. 4 is a perspective view showing two tiles, one partly broken away, the two tiles being spaced slightly apart to show the interengaging tab portions before the two tiles

30 are brought together.

Fig. 5 is a perspective view partly broken away of two tiles like those shown in Fig. 4 taken at a different angle for the purpose of showing in full the upper tab on the tile which is only partly shown in Fig. 4.

Fig. 6 is a perspective view showing the rear face of a single tile to show more clearly in detail the construction of the flanges and of the nailing tabs.

40 Fig. 7 is a plan view of a flat blank after it is died out and before the flanges and tabs are turned into position for the finished tile.

Before explaining in detail the present invention, it is to be understood that the invention is not limited in its application to the details of construction and arrangement of parts illustrated in the accompanying drawings, since the invention is capable of other embodiments and of being practised or 45 carried out in various ways. Also it is to be

understood that the phraseology or terminology employed herein is for the purpose of description and not of limitation, and it is not intended to limit the invention beyond the terms of the several claims hereto appended as considered in view of the prior art and the requirements thereof.

55 Each tile is made of a flat piece of sheet metal cut out to the proper contour as shown in Fig. 7 having a main body portion 10, two side flange portions 11, 12, two end flange portions 13, 14 and two nailing tab portions 15, 16. Each of the tabs is formed with a nailing hole 17. The two tab portions 15, 16 are offset from each other, one being nearer to the upper side edge of the panel portion of the blank and the other tab being nearer to the opposite side edge of the panel portion of the blank, each tab being at the same distance as the other tab from the nearest side edge of the flange from which it projects.

60 The flanges 11, 12, 13 and 14 are all turned at right angles to the body portion 10 as shown in Fig. 6, and the tab members 15, 16 are bent at right angles to the planes of the end flange portions 13, 14.

65 Each end flange member is slightly undercut on a portion of its lower edge intermediate the end portions of the flange member, forming a recess 19 between the tab 15 and the shoulder portion 18 of the flange member 13 and forming a recess 21 between the tab 16 and the shoulder portion 20 of the opposite flange member so that when the tiles are laid in courses there will be left a thin space equal to the depth of the recesses 19 or 21 between the edge of the recessed portion of the flange and the face of the wall to receive the tab of the adjacent tile as shown in Figs. 2 and 3.

70 It is important that the under face of each tab shall be in a plane with the edge of the wider portions of the flanges 13, 14 or at least that the under face shall not be below the edge of said wider portions shown at 23, 24. In order to insure that they may be so bent the blank is preferably formed with slits 22 as shown in Fig. 7, the slits extending in far enough so that when the tabs are turned

100

over as shown in Fig. 6 the under face of the tab shall be in the same plane as the edge of the wider portions of the flange near the ends thereof. Without such slits or some other provision for taking up the thickness of the metal, the plane of the tab is liable to be below the edge of the flange an amount equal to the thickness of the metal plate.

In Figs. 2 and 3 the tiles are shown as secured by nails 26 to joists 27 fastened to the wall 28.

In laying the tiles and attaching them to the wall, the tab at one end only of the tile is nailed to the wall because if one tile is laid and nailed and the next tile in order is positioned with one of its tabs in engagement with the adjacent recess of the preceding tile that tab will necessarily be covered up by the said preceding tile and is inaccessible for nailing. Therefore, only the exposed tab at the outer end of the last laid tile will be nailed and in turn the third tile will then be laid and nailed in the same manner, one tab being covered up by the second tile and the exposed tab of the third tile will be nailed. The covered up tab is useful however as a guide in positioning the tile in proper alinement with the adjacent preceding tile, although it is not essential for that purpose because the advance tab of the said preceding tile also serves as a guide. The main purpose of having a tab at each end and having them offset from each other, that is, one tab near the upper edge and the other, tab correspondingly near to the lower edge, is to permit the tiles to be laid up either end foremost according to convenience or mere random choice.

What we claim is:

1. A sheet metal tile having a body portion, flange portions at the sides and ends extending in planes at right angles to the plane of the body portion, the end flanges each having end portions of greater width than the intermediate portion thereby forming a recess between said two wider end portions, each flange having adjacent one of said wider portions a tab which projects in a plane at right angles to the flange and parallel with the said body portion, said tab being in a plane no part of which projects below the outer edge of the wider portions of the flange.
2. A sheet metal tile having a main body portion, flange portions projecting from two opposite ends thereof in planes at right angles to the body portion, said flanges having a portion at each end thereof of greater width than the intermediate portion, thereby forming a recess between said wider end portions, a tab projecting from each of said flanges in a plane parallel with the body of the tile, the lower face of the said tab being in the same plane as the edge of the wider portion of the flange, the tabs at the opposite ends being ad-

70 jacent diagonally opposite corners of the tile and spaced at equal distances from the respective adjacent corners.

3. A sheet metal tile having flanges at two opposite ends thereof which extend at a right angle to the plane of the body portion of the tile, said flanges being recessed for a portion of their length between two opposite end portions of their length between two opposite end portions, a tab projecting from the narrower portions of each of said flanges adjacent one end of said recess and lying wholly in a plane with the edge of said narrower portion, said two tabs being adjacent diagonally opposite corners of the tile.

35 4. A sheet metal tile having flanges at two opposite ends thereof extending at right angles to the plane of the body portion of the tile, said flanges being recessed for a portion of their length between two opposite end portions of greater width than said recessed intermediate portion, a tab projecting from the narrow portion of each of said flanges adjacent one of the wider end portions, said tab being bent at right angles to said flange into a plane with the lower edge of said wider portion.

5. A sheet metal tile having a rectangular body portion, flange portions extending from two opposite edges thereof at right angles to the plane of said body portion, each of said flanges having a recess in its edge, a tab integral with each of said flanges and extending at right angles thereto in a plane parallel with said body portion, the under face of said tab being in a plane which does not extend below any part of the said flange.

6. A sheet metal tile having a rectangular body portion, flange portions extending from two opposite edges thereof at right angles to the plane of said body portion, each of said flanges having a recess in its edge, a tab integral with each of said flanges and extending at right angles thereto in a plane parallel with said body portion, the said flange being formed with a slit extending at right angles to its outer edge adjacent said tab whereby said tab may be bent into a plane whose lower face does not extend below the lower edge of the wider portion of the flange.

7. A sheet metal tile having a rectangular body portion, flange portions extending from two opposite edges thereof at right angles to the plane of said body portion, each of said flanges having a recess in its edge, a tab integral with each of said flanges and extending at right angles thereto in a plane parallel with said body portion, the under face of said tab being in a plane which does not extend below any part of the said flange, the tab portions at the opposite ends of the tile being offset from each other and adjacent diagonally opposite corners of the tile, one tab being nearer one end of the recessed portion of the flange with which it is connected and the other

tab being nearer the opposite end of the recessed portion of the flange with which it is connected.

8. A sheet metal tile having a body portion and a flange at each of two opposite ends thereof extending at right angles to the plane of the body of the tile, each of said flanges having a recess in its edge intermediate the ends of said flange whereby said flange has two end portions of greater width than said intermediate portion, a tab projecting from each of said flanges intermediate one of said wider portions and said narrower portion of the flange, and extending in a plane parallel with said body portion, said tabs being offset from each other so that one of them is nearer one side edge and the other tab is correspondingly nearer to the opposite side edge whereby in setting up a plurality of tiles to form a facing either end of the tile is adapted to interlock with either end of the adjacent tile in the same course.

In testimony whereof we affix our signatures.

EDWARD L. C. CLARK.
